UNITED STATES PATENT OFFICE.

STANLEY L. FISHER, OF CHESTER, CONNECTICUT, ASSIGNOR TO PRATT READ PLAYER ACTION COMPANY, OF DEEP RIVER, CONNECTICUT.

AUTOMATIC MUSICAL INSTRUMENT.

Application filed October 23, 1920. Serial No. 418,876.

To all whom it may concern:

Be it known that I, STANLEY L. FISHER, a subject of the King of Great Britain, residing in Chester, county of Middlesex, State 5 of Connecticut, have invented certain new and useful Improvements in Automatic Musical Instruments, of which the following is a full, clear, and exact description.

This invention relates to automatic musical instruments, and particularly to that type of the same which employ a pneumatic action in their operations. It is particularly adapted for use in a player piano or similar type of instrument which employs air under 10 exhaust tension to operate the hammers or keys; but it will be apparent to those skilled in the art that the principle of the invention may be applied without material modification to a piano or wind organ which employs air under pressure. The terms "exhaust tension" and "air under pressure" are used to designate respectively pressures less than and greater than that of the atmosphere. The invention is particularly 15 concerned with the provision of an improved device for regulating and producing changes in the air pressure obtaining within the wind chest of the instrument.

One object of this invention is to provide a new and improved expression device for this class of instruments.

A further object of the invention is to provide an expression device which will produce promptly responsive changes in playing 35 intensities.

A still further object of the invention is to provide an expression device which may be controlled with ease and from which the changes in expression may be obtained by a slight pressure on the controlling lever.

A further object of the invention is to locate the expression regulator without the main air circuit, so that the air drawn from the wind chest does not pass through the 45 regulating pneumatic.

To these and other ends the invention consists in the novel features and combinations of parts to be hereinafter described and claimed.

50 In the accompanying drawings:

Fig. 1 is an elevational view of a part of a pneumatic action which embodies my invention;

Fig. 2 is a side view of the same.

Fig. 3 is a sectional view of the regulating pneumatic on line 3—3 of Fig. 1. 55

Fig. 4 is a view similar to Fig. 3, some parts being broken away and showing the regulating pneumatic in another position.

Fig. 5 is a section through the regulating pneumatic on line 5—5 of Fig. 1.

Fig. 6 is a section through the valve chest on line 6—6 of Fig. 1.

Fig. 7 is a plan view of the regulating pneumatic and the valve chest with the covers removed on line 7—7 of Fig. 5.

Fig. 8 is a diagrammatic sectional view on line 8—8 of Fig. 1.

Musical instruments of this type are usually provided with a reservoir, which is in communication with an exhausting device of some preferred type. The reservoir is usually connected with a wind chest which serves to supply the power for operating the playing pneumatics. There is usually located in this connection between the reservoir and the wind chest a regulating valve which will control the communication between the chest and the reservoir and in this way will regulate the degree of exhaust that is obtained in the wind chest. The embodiment of my invention which I have chosen to show and describe will preferably contain the elements named above.

In Figs. 1 and 7, I have shown a reservoir 85 at 11, a duct 12 leading to a valve chest 13 in which the regulating valve 14 is placed. The valve 14 may be of any approved type; the one shown, however, being a flap valve 90 which is composed of the two flaps 15 and 16, the flaps having a lost motion connection at 17, so that when the upper flap is raised to any great extent, the lower one will also be raised and will permit the passage of air 95 through the port 18, through which the duct 12 communicates with the valve chest 13. The valve 14 is substantially the same as the expression valve shown and described in my Patent No. 1,404,106 granted Jan. 17, 1922. At its rear end the valve is hinged to the bottom of the valve chest, so that the forward end is free to swing upwardly and permit the passage of air through the port 18. There is also in the valve chest an opening 19, which communicates with a duct 20 extending to the wind chest 21, which supplies the player actions. 100

It will be apparent that a movement of

the valve 14 about its hinged end will control the communication between the wind chest 21 and the reservoir 11, the air from which is exhausted by suitable exhausting means 10, and, therefore, the degree of exhaust obtained in the wind chest will be suitably regulated. The wind chest 21 may be of the divided type, and if so, a similar valve box and expression mechanism will be placed at the other end of the same, and it will be understood that in this case the expression mechanism shown in Fig. 1 would be duplicated at the right hand end of the pneumatic action, it being located at the left hand end, as shown.

A link 22 is hinged to the flap 16 of the valve 14 and extends through an opening in the top of the valve chest 13, the projecting end of the same being provided with a block 23, which may be adjustably secured to the link by a set screw 24. The position of the valve is controlled by this link.

A regulating pneumatic 25 is, as shown, also an expression pneumatic, and for this reason I refer to the same as an expression regulator. The movable leaf 26 of this pneumatic is hinged at 27, the lower end of the same being free to swing in the usual manner. A stop 28 is provided on an adjustable screw 29 extending through the movable leaf 27 in order to limit the collapsing movement of the movable leaf 26. The expansion of this pneumatic is limited by the adjustable stop 30 which cooperates with a slotted lug 31 secured to the upper surface of the movable leaf 27. A small block 32 is also secured to the movable leaf of the pneumatic and is provided with a rod 33 which extends laterally from the pneumatic under the block 28, which is secured to the link 22, which serves to control the position of the valve. With this arrangement it will be apparent that upon the collapse of the expression regulating pneumatic, the regulating valve 14 will be allowed to be drawn down nearer its seat over the port 18 and upon the expansion of the regulating pneumatic, the valve will be drawn away from the port by the rod 33, and the link 22, so that a less restricted communication will be permitted between the reservoir and the wind chest, and hence the exhaust tension in the wind chest will be raised.

In the lower leaf of the pneumatic 25 is a restricted port 25^a, which is in communication with a duct 25^b, leading to the port 19. The regulating pneumatic is thus in constant communication with the wind chest through this restricted port and the passages 25^b and 20.

To control the collapse and expansion of the expression regulator, I have provided a manually controllable lever 34, which may be located in the key slip 35 of the piano

or musical instrument with which my invention is to be used. To the lower end of the lever 34 is secured a rock shaft 36, which is more or less horizontally disposed and extends rearwardly beneath the key board 70 of the instrument and has secured to its other end a rock arm 37. To this arm 37 is secured a link 38, the other end of which is connected to a rock arm 39 secured to a shaft 40, which extends transversely across 75 the instrument, and is provided near one end with a second rock arm 41. The free end of this rock arm 41 is flattened and perforated to receive the threaded end of a link 42, which is provided with a nut 43 80 to limit the movement of the rock arm with respect to the link. As shown, the nut 43 may be adjusted with respect to the link 42 for a purpose to be hereinafter described. To the end of the link 42, which is remote 85 from the rock arm 41, is secured one end of the regulating spring 44, the other end of which is secured to a lever 45, which is connected with the movable leaf of the expression regulator to control the same. It 90 will be seen that if the lever 34 is moved to the left, as shown in Fig. 1, by the operator, the shaft 40 will be rocked in its bearings 40^a (only one of which is shown, but it will be understood that a similar bearing is 95 located at the other side of the pneumatic action) and the movable leaf of the pneumatic will be raised about its hinged end through the rock arm 41, the spring 44 and the lever 45. When the lever 34 is set at 100 any given position, the degree of exhaust which obtains in the wind chest will naturally be controlled and uniformly regulated by the tension of the spring 44. It is thus seen that when the lever is in the position 105 shown in Fig. 1, the minimum degree of exhaust possible in the wind chest will obtain. This minimum degree may, of course, be regulated by an adjustment of the nut 43 on the stem 42. The instrument will then 110 be playing its tones of lowest intensity or pianissimo. When the lever is moved to the left, as shown in Fig. 1, the tones which will be produced by the instrument will gradually grow louder in intensity, according to 115 the increase in intensity of the exhaust obtaining in the wind chest, the loudest tones, of course, being produced when the lever is moved as far to the left as possible.

It has been discovered that if the lever 45 120 is connected directly to the movable leaf 26 of the expression regulator, the opening of the movable leaf of this pneumatic will exert considerable force to resist the movement of the lever 34 to the left in Fig. 1 at 125 certain times in the operation of the instrument. In order to overcome this difficulty, I have connected this lever to the pneumatic in a novel way. The movable leaf of the pneumatic is provided with a small port 46, 130

which is normally closed by a flap valve 47 positioned at a point adjacent the hinged end of the regulating pneumatic. To the upper surface of this flap valve is secured 5 the lower end 49 of the lever 45. A screw eye 50 is passed loosely through the flap valve 47 and is screwed into the movable leaf 26. The shank of this screw eye is passed loosely through a perforation in a 10 leaf spring 51, which is bowed, as shown in Figs. 2, 3 and 4, the two ends resting on the end 49 of the lever 45. A washer 52 may surround the shank of the screw eye between the spring and the head of the 15 screw. The shank of the screw eye, as shown, passes loosely through the flap valve 47, so that this valve is free to move about the opposite end relative to the movable leaf 26 of the expression regulator, as shown 20 in Fig. 4. The valve 47 is, however, normally kept in contact with this movable leaf by the pressure of the ends of the spring 51, which reacts against the screw eye 50 and is held in position by a pin 53 25 which is secured to the flap valve and engages in a slot 54 in one end of this spring.

The opening 25^a through which the regulating pneumatic is exhausted is preferably smaller than the port 46 through which atmospheric air is admitted to the pneumatic when the valve 47 is raised. By means of this arrangement the air admitted to the pneumatic will not be at once drawn through the restricted opening 25^a by the 30 exhaust obtaining within the instrument, but will remain to some extent within the pneumatic and assist in effecting the opening of the same.

When the valve 47 is raised out of contact with the movable leaf of the regulating pneumatic, this pneumatic will be flushed with air through the port 46 and the tension which exists within the same will be immediately lowered. This will result in 40 the pressure within the regulating pneumatic becoming more nearly that of the atmospheric air without the pneumatic and the force of the air tending to close the pneumatic or to resist its opening will, of course, be reduced. For this reason, when the regulating pneumatic is about to be opened by the lever 34 and a strong resistance to such opening is offered, the valve 47 will be raised, as shown in Fig. 4, the 45 interior of the regulating pneumatic will be flushed with air, and it will immediately follow the valve upwardly and its opening will be accomplished with greater ease. With this arrangement the maximum pull 50 which is ever necessary on the lever 34 will be that which is sufficient to overcome the force with which the spring 51 holds the valve 46 in contact with the movable leaf of the regulating pneumatic.

As has been stated my improvements may

be used with a "divided" pneumatic action, and in this case, the expression devices shown will be duplicated at each end of the wind chest. While in Fig. 1 only one end of the rod 40 is shown, it is to be understood that in case of the use of a divided action, the other end of this rod will be provided with a rock arm 41, which will control a spring 44, lever 45 and valve 46, together with the expression pneumatic 25 70 and valve 14, all as shown and described for use at the left hand side of the instrument. It will be seen that the lever 34 will thus control the expression for both the base and the treble ends of the instrument simultaneously. 75

The operation of my device is as follows:

When the exhausting devices 10 are placed in operation, the air will be exhausted from the reservoir 11 and through the duct 12 80 from the valve chest 13 past the regulating valve 14, through the port 19 and duct 20 from the wind chest 21. The regulating pneumatic 25 being in communication with the wind chest will be acted on by the exhaust tension obtaining therein and hence 85 will tend to collapse and close the regulating valve 14. This collapse will be resisted by the spring 44, the lever 34 being in its extreme right hand position, as shown in 90 Fig. 1. The valve 14 will close until a balance is obtained whereby the tension of the spring 44 will be sufficient to overcome the 95 tendency of the atmosphere upon the outside of the regulating pneumatic 25 to close 100 the same. This will be the position of the parts when a minimum degree of exhaust obtains in the wind chest, and the lowest tones are being obtained from the instrument, as shown in Fig. 6. Now if it is 105 desired to produce louder tones, the lever 34 is moved to the left, as shown in Fig. 1, and the regulating pneumatic 25 will be opened through the rock shaft 40, the rock 110 arm 41, the rod 42, and the spring 44, thus raising the regulating valve 14 from its seat, as shown in Fig. 4; and permitting a less restricted communication between the wind chest and the reservoir. When pressure is applied to the lever 34, if the 115 resistance offered by the movable leaf of the regulating pneumatic 26 is sufficiently great to overcome the pressure of the spring 51 on the flap valve 47, this valve will be raised from its seat and the regulating pneumatic will be flushed with air to a sufficient extent to permit its being opened more easily and thus relieve the pressure against the fingers of the operator manipulating the 120 lever 34. As has been stated, the regulating pneumatic is in communication with the wind chest through a restricted port, so that a sufficient amount of air may be admitted through the port 46, to affect the degree of 125 exhaust within the regulating pneumatic 130

without materially affecting the exhaust tension obtaining in the wind chest.

While I have shown a specific embodiment of my invention, as applied to a pneumatic musical instrument of the exhaust type, it will be understood that the invention is not to be limited to the exact details shown, but is susceptible of many changes and various embodiments which will fall within the spirit of the invention and within the scope of the appended claims and that with but slight modifications familiar to those skilled in the art, the same may be readily applied to pneumatic musical instruments of the pressure type.

What I claim is:

1. In a pneumatic musical instrument, an action chest, an exhausting device therefor and communicating therewith, a regulating valve controlling said communication, a regulating pneumatic controlling said valve, said pneumatic being connected with the action chest by a restricted port.
2. In a tension graduating device, a valve box, a tension controlling valve therein, and a regulating pneumatic mounted without said box and connected to said valve, the interior of said pneumatic being in communication with the controlled tension through a restricted port.
3. In a tension graduating device, a valve box, a tension graduating valve therein, a controlling pneumatic mounted without said box and operatively connected to said valve, the interior of said pneumatic being in communication with said valve box through a restricted port.
4. In a pneumatic tension graduating device, a valve box having fixed walls, a tension graduating valve therein, a link connected to said valve and projecting from said box, and a tension controlling pneumatic having its movable leaf operatively connected to said link without said box, and being in constant communication with the graduated tension.
5. In a pneumatic tension graduating device, a valve box having fixed walls, a tension graduating valve therein, a link connected to said valve and projecting from said box, and a tension regulating pneumatic having its movable leaf adjustably connected to said link exteriorly of said box.
6. In a pneumatic tension graduating device, a valve box, a tension graduating valve therein, a link connected to said valve and projecting from said box, and a tension controlling pneumatic having its movable leaf operatively connected to said link, said connection including a block secured to said link, and a part secured to said movable leaf and engaging said block.
7. In a pneumatic tension graduating device, a valve box, a tension graduating valve therein, a link connected to said valve and

projecting from said box, and a tension controlling pneumatic having its movable leaf operatively connected to said link, said connection including a block connected to said link and a part secured to said movable leaf and projecting laterally therefrom to a point below said block.

8. A tension controlling pneumatic normally subjected to exhaust tension, the movable leaf thereof having an atmosphere port, a valve co-operating with said port and expanding means for the pneumatic connected to said valve.

9. A tension controlling pneumatic normally subjected to exhaust tension, the movable leaf thereof having an atmosphere port, a spring pressed valve co-operating with said port and expanding means for the pneumatic connected to said valve.

10. In a pneumatic tension graduating device, a tension graduating valve, a regulating pneumatic having its movable leaf operatively connected with said valve, expression varying means connected to said leaf to move the leaf to change the regulation by said valve, said means being arranged to admit air to said pneumatic to facilitate the movement of the same.

11. In a pneumatic tension graduating device, a regulating pneumatic, a tension graduating valve moved to high tension position by the opening of said pneumatic, means to exert an opening pull on said pneumatic and said means being arranged to admit air to said pneumatic to facilitate the opening thereof.

12. In a pneumatic tension graduating device, a regulating pneumatic, a tension graduating valve controlled by the movable leaf thereof, expression varying means connected to said leaf to open the same and said means being arranged to admit air to said pneumatic to facilitate the opening thereof.

13. In a pneumatic tension graduating device, a source of exhaust, a tension graduating valve for controlling the degree of exhaust produced by the same and a regulating pneumatic controlling said valve, said pneumatic being in unvarying communication with the exhaust tension controlled by said valve, and having a port through which atmosphere may be admitted at intervals.

14. In an expression device, a controlling pneumatic normally subjected to air tension, means to exert an opening pull on the movable leaf thereof, and means to admit air to said pneumatic to decrease the tension therein when said opening means is actuated.

15. An expression regulating pneumatic, a tension graduating valve controlled by the movable leaf thereof, expression varying means connected to said movable leaf to move the same to vary the position of said valve, said movable leaf having a port, and

said connections including a valve cooperating with said port.

16. A wind chest, and an expression regulating pneumatic in constant communication with the wind chest through a relatively restricted port, and provided with a valved atmosphere port through which air may be admitted to said pneumatic and means to exert an opening pull on said pneumatic to increase the degree of exhaust regulated thereby.

17. In a pneumatic tension graduating device, an expression regulating pneumatic, a tension graduating valve controlled by the movable leaf of said pneumatic, expression varying means connected to said movable leaf to move the same and the valve controlled thereby, said pneumatic being provided with an atmosphere port and said connection including a valve normally closing said port.

18. In a pneumatic tension graduating device, an expression regulating pneumatic, a tension graduating valve controlled by the movable leaf of said pneumatic, expression varying means connected to said movable leaf to move the same and the valve controlled thereby, said pneumatic being provided with an atmosphere port and said connection including a spring pressed valve normally closing said port.

19. In a pneumatic tension graduating device, an expression regulating pneumatic, a tension graduating valve controlled by the movable leaf of said pneumatic, expression varying means connected to said movable leaf to move the same and the valve controlled thereby, said pneumatic being provided with an atmosphere port and said connection including a spring pressed valve normally closing said port, but admitting air to said pneumatic when the pull on said moving means exceeds a predetermined amount.

20. In a pneumatic tension graduating device, an expression regulating pneumatic, a tension graduating valve controlled by the movable leaf of said pneumatic, expression varying means connected to said movable leaf to move the same and the valve controlled thereby, said pneumatic being provided with an atmosphere port and said connection including a spring pressed valve normally closing said port, a lever secured to said valve and projecting from the same at one end and means to actuate the free end of said lever to move said leaf.

21. In a pneumatic tension graduating device, an expression regulating pneumatic, a tension graduating valve controlled by the movable leaf of said pneumatic, expression varying means connected to said movable leaf to move the same and the valve controlled thereby, said pneumatic being provided with an atmosphere port and said connection including a spring pressed valve nor-

mally closing said port, a lever secured to said valve and projecting from the same at one end and means to actuate the free end of said lever to move said leaf, said valve opening said port when the pull on said lever overcomes the force of said valve spring.

22. A wind chest, a tension graduating valve controlling the degree of exhaust therein, a regulating pneumatic in communication with the controlled exhaust for controlling said valve, means to exert an opening pull on the movable leaf of said pneumatic to vary the position of said valve, and means to limit the resistance of the pneumatic to said pull to a predetermined amount.

23. In a pneumatic tension graduating device, an expression regulating pneumatic, a tension graduating valve controlled by the movable leaf of said pneumatic, expression varying means connected to said movable leaf to move the same and the valve controlled thereby, said pneumatic being provided with an atmosphere port and said connection including a spring pressed valve normally closing said port, and means to exert an opening pull on said valve, said pull being communicated to the movable leaf of said pneumatic by said valve spring.

24. An expression regulating pneumatic, a tension graduating valve controlled by the movable leaf thereof, expression varying means connected to said movable leaf to move the same to vary the position of said valve, said movable leaf having a port and said connections including a valve cooperating with said port and spring-pressed into engagement with said movable leaf.

25. An expression regulating pneumatic, a tension graduating valve controlled by the movable leaf thereof, expression varying means connected to said movable leaf to move the same to vary the position of said valve, said movable leaf having a port and said connections including a valve cooperating with said port and spring-pressed into engagement with said movable leaf, and means to exert a pull on said valve to move said movable leaf.

26. An expression regulating pneumatic, a tension graduating valve controlled by the movable leaf thereof, expression varying means connected to said movable leaf to move the same to vary the position of said valve, said movable leaf having a port and said connections including a valve cooperating with said port and spring-pressed into engagement with said movable leaf, and means to exert a pull on said valve to move said movable leaf, said valve opening said port to admit air to said pneumatic when said pull overcomes said valve spring.

27. An expression device including means presenting an air port, a pneumatic controlling the passage of air therethrough, ex-

5
pression varying means to exert an opening pull on said pneumatic and means to admit atmospheric air to said pneumatic to facilitate the opening of the same to vary the control of the passage of air through said port.

28. In an expression device, a chamber normally containing air under exhaust tension, an expression pneumatic communicating therewith by a relatively restricted port and said pneumatic having a movable leaf containing an atmosphere port.

29. In an expression device, an expression controlling pneumatic constantly subjected to air tension, means controlled by said pneumatic to cause an increase in the air tension upon an opening movement of the movable leaf thereof, a manually operable expression lever connected to said movable leaf, and means actuated by said lever to admit atmospheric air to said pneumatic to effect such opening movement.

30. An expression device including means presenting an air port, a pneumatic controlling the passage of air therethrough, and means to admit atmospheric air through the movable leaf of said pneumatic to effect the opening of the same to vary the control of the passage of air through said port.

31. In an expression device, a controlling pneumatic, a regulating spring connected to said pneumatic, means to vary the tension upon said spring to vary the regulation thereby, said connection including a valve, and said pneumatic being provided with an atmosphere port controlled by said valve.

32. In an expression device, a controlling pneumatic normally subjected to air tension, means to exert an opening pull on the movable leaf thereof, and a valved port opened by said means to admit air to said pneumatic to facilitate the opening thereof.

33. In an expression device, a controlling pneumatic, a manually operable expression lever connected to the movable leaf thereof, said connection including a regulating spring and a valve movably mounted upon the movable leaf of the pneumatic, and said

leaf being provided with an atmosphere port controlled by said valve.

34. In a pneumatic tension graduating device, a controlling pneumatic normally subjected to air tension, a tension graduating valve moved to high tension position by the opening of said pneumatic, means to exert an opening pull on the pneumatic, and means controlled thereby to admit air to the pneumatic to facilitate the opening thereof.

35. In a pneumatic tension graduating device, an expression regulating pneumatic, means connected to the movable leaf thereof by which the same may be opened to vary the regulation of said pneumatic and means by which atmospheric air is admitted to said pneumatic when said opening means is actuated.

36. In a pneumatic tension graduating device, an expression regulating pneumatic, means connected to the movable leaf thereof by which an opening pull may be exerted thereupon to vary the regulation by the pneumatic, and means set into operation when said opening pull is exerted to lessen the resistance of the pneumatic to said pull.

37. In a pneumatic tension graduating device, a regulating pneumatic, a tension graduating valve controlled by the movable leaf thereof, expression varying means mechanically connected to said leaf to open the same and means responsive to the actuation of said mechanically connected means to lessen the resistance of the movable leaf to said expression varying means.

38. An expression device, including means presenting an air port, a pneumatic controlling the passage of air therethrough, expression varying means to exert an opening force upon the movable leaf of said pneumatic, and means responsive to said exerted force to admit atmospheric air to said pneumatic to facilitate the opening thereof.

In witness whereof, I have hereunto set my hand on the 20th day of October, 1920.

STANLEY L. FISHER.
